UNITED STATES PATENT OFFICE.

WILLIAM J. DOBKIN, OF CHICAGO, ILLINOIS.

COIN-CONTROLLED LOCK.

Application filed December 21, 1925. Serial No. 76,859.

My invention relates to improvements in coin-controlled locks, and it consists in the combinations, constructions, and arrangements herein described and claimed.

An object of my invention is to provide a coin-controlled lock which consists of a number of coacting parts for permitting the key to lock the door of the locker to which the device is attached only after a coin has been inserted in the lock. The lock is further provided with novel means for permitting the key to be turned into locked and unlocked position as many times as desired previous to the removing of the key from the lock. A further feature of the device lies in the means for blocking the coil entrance when the key is removed, this same means also actuating a stop which prevents the removal of the key and the locking of the lock until a coin has been inserted in the lock.

A further object of my invention is to provide a coin-controlled lock in which the lock is provided with an indicator for showing the number of times the locker has been used, this indicator being operated only when the key is removed from the lock. The indicator further cooperates with a light for showing whether the locker is unlocked or locked.

A further object of my invention is to provide a coin-controlled lock in which novel means is provided for removably securing the lock casings in the lockers, whereby the entire lock casing may be removed in case the key to the casing is lost and a new lock be substituted for the one removed.

Other objects and advantages will appear in the following specification, and the novel features of the invention will be particularly pointed out in the appended claims.

My invention is illustrated in the accompanying drawings, forming part of this application, in which—

Figure 1 is a front elevation of the device with the cover plate removed, and showing the lock in unlocked position,

Figure 2 is a view similar to Figure 1, showing the lock in locked position,

Figure 3 is a fragmentary view showing the arrangement of the parts when the casing is turned without first placing a coin in the lock,

Figure 4 is a section along the line 4—4 of Figure 6, 55

Figure 5 is a section along the line 5—5 of Figure 1,

Figure 6 is a front elevation of the lock showing the lock assembled in the locker,

Figure 7 is a diagrammatic view showing 60 how a number of locks are secured in the locker, and

Figure 8 is a diagrammatic plan view of one of the lockers.

The invention is designed especially for 65 metal cabinets intended for the use of parcel checking lockers in public places, such as dance halls, hotels, railway waiting rooms, drug stores, etc. The cabinets are normally open and are usually arranged in 70 tiers having four lockers in each tier. One of the locks is provided for each locker and is adapted to lock the door 1 in closed position. The cabinet is preferably constructed of sheet metal and this metal is bent into a 75 U-shape, as shown in Figure 8, and the open front of the cabinet is provided with hollow spaces 2. In the right hand hollow space, I dispose the locks, one lock being 80 provided for each locker.

I will now describe the specific construction of the lock and reference is made to Figures 1, 2 and 3. The lock comprises a body portion 3, a cover plate 4 and a key-actuated mechanism. The body portion 3 85 carries a key-receiving cylinder 5. The cylinder 5 is rotatably mounted in the body portion 3 and carries an arm 6. The arm is moved when the cylinder 5 is rocked by the key, and in turn moves a locking bolt 7. It 90 will be noted that the bolt 7 has a notch 8 therein for loosely receiving a pin 9 carried by the arm 6. This construction permits the cylinder 5 to be rocked slightly before the pin 9 will move the locking bolt 7 into locked 95 position. The purpose of this will be hereinafter set forth.

The arm 6 has a toothed quadrant 10 which meshes with a mutilated pinion 11. The quadrant 10 and the pinion 11 are provided for actuating a novel stop mechanism for the cylinder 5, an indicating mechanism, and a coin passage-closing member. The means for actuating the stop mechanism, the indicator mechanism, and for closing the 105 coin passage consists of a lever 12. This

lever is pivotally secured to the body portion 3 at 13 and is operatively connected to the pinion 11 by what I term a floating spring. This spring has one of its ends secured to the lever 12 by a pin 15 and has its other end secured to an arm 16 of the pinion 11 by a pin 17.

It should be noted at this point that the spring 14 exerts a pressure upon the lever 12 at a point which is almost at the dead center of the lever, for if the pin 15 were lowered so as to be disposed in a line drawn between the pins 17 and 13, the force of the spring upon the lever 12 would have no effect, since it would be exerted on the line of dead center. The spring 14 therefore exerts a slight force against the lever 12.

This is not true with the other end of the spring, because it will be noted from Figure 1 that the spring 14 exerts a pressure against the pinion 11 substantially at right angles to the dead center line of the pinion. A greater force will therefore be exerted upon the pinion than upon the lever 12. The lower end 18 of the lever 12 engages with a lug 19 carried by a stop member 20 and tends to swing the stop member toward the arm 6. The arm is provided with a notch 21 for receiving the stop member 20 when no coin has been inserted in the lock, whereby the arm is prevented from further movement. The spring 14 causes the arm 6 to keep the stop 20 in normal position.

The recess 8 permits the arm 6 to be moved slightly without moving the bolt, and this movement swings the arm 6 away from the stop member 20 and permits the lever 12 to move the stop member 20 toward the arm to bring the upper edge 22 into engagement with the notch 21. The cylinder 5 is now prevented from further rotation in a clockwise direction when looking at Figure 1. The position of the parts is clearly shown in Figure 3.

The lever 12 is further provided with a lug 23 for stopping the passage of the coin through the coin slot 24, see Figures 1 and 4. The coin is inserted in the slot and drops down onto a projection 25. This projection is disposed directly in back of the lug 23. The projection 25 and the lug 23 prevent further movement of the coin until the key has been removed. After the coin has been inserted, the key cylinder 5 may be rotated to the right, and this movement will swing the arm 6 into the position shown in Figure 2, and will also swing the arm 16 into the position shown in Figure 2. The stop 20 abuts the coin and permits this movement.

This movement causes the floating spring to exert a pressure upon the arm 16 in a direction opposite to that which it formerly exerted. In other words, the arm 16 in Figure 1 has a tendency to swing in a clockwise direction, due to the force of the spring 14, and

in Figure 2, has a tendency to swing in a counter-clockwise direction, due to the force of the same spring 14. The spring therefore aids in moving the parts into locked and unlocked position.

When the key has moved the bolt 7 into locked position, see Figure 2, the lever 12 will have a tendency to swing into the full line position shown in the figure, due to the force of the spring 14 in changed position. A projection 26 carried by the lever 12 contacts with the cylinder 5 and prevents this movement. However, the cylinder 5 has a recess 27 therein for receiving this projection when the cylinder 5 has been rotated into the position shown in Figure 2. Figure 2 shows the key slot as being large enough for the insertion of a key that will prevent the projection from being received in the recess 27 so long as the key remains in the lock. This permits the key to be turned from locked to unlocked position and back to locked position as many times as desired. In the locks now on the market, a turning of the key will release the coin, even though the key is not removed from the lock, and then a subsequent turning of the key into unlocked position will prevent the key from again being turned into locked position, unless another coin is inserted in the lock. Many persons checking packages, seeing the locker doors closed, do not know whether the doors are locked or unlocked, and of course assume that the doors are locked. They then drop the coin in the slot, turn the key to apparently unlock the door, and find out instead that they have locked the door. It is now necessary for the door to be unlocked, and after doing so, the mechanism is prevented from again being moved into locked position, unless another coin is put in the machine. With the special construction just described, I overcome this disadvantage, and, as heretofore stated, permit the lock to be locked and unlocked as many times as desired, so long as the key remains in the lock.

As soon as the key is removed from the lock, the projection 26 is received in the recess 27 and the lever 12 will now swing into the full line position shown in Figure 2. The upper end 28 of the lever 12 will swing to close the coin entrance 29, see Figure 6. This movement is accomplished by the spring 14. The swinging of the lever 12 will also remove the projection 23 from beneath the coin 30, and will permit the coin to pass on through the coin passageway 24.

The lock carries an indicating mechanism 31 and the arm 32 of this mechanism is connected to the lever 12 by means of a link 33. The link 33 advances the indicator one digit when the key is removed from the lock. The opening of the lock actuates the arm 6, the quadrant 10, the pinion 11, and the lever 12

for moving these parts back into the position shown in Figure 1. The lock is now ready to again be operated.

When the parts are in open position, the 5 arm 32 contacts with a spring terminal 34. The terminal is insulated from the body portion 3 and is in electrical connection with a light 35. A wire 36 leads from the light and is in electrical connection with a 10 source of current. When therefore the lock is open, current will flow through the wire 36 to the light 35, thence to the arm through 32 through the medium of the flexible terminal 34. The arm 32 is in electrical connection 15 with the electrical source of current. The light is now energized and will remain so until the lock is again actuated. A lens 37 is disposed in front of the light and is carried by the cover plate 4.

20 Due to the position of the floating spring 14, the action of the spring brings the forces exerted by the arm 6 and the stop member 20 against one another. The stop member 20 is moved back into operative position by 25 the lever 12 which engages with the lug 19. The left hand lug 38 in Figure 1 contacts with the coin and prevents the movement of the stop member 20, whereby the parts may be moved into locked position. It should 30 be noted at this point that the bolt 7 moves in front of the door 1, see Figure 5, when locking the door.

In Figures 6 and 7, I show a novel means for securing the lock casings in the cabinets. 35 The front wall indicated by the letter *x*, see Figures 6 and 8, has openings 39 therein for receiving the lock casings. The openings are shorter in length than the length of the lock casings. In Figure 2, I show 40 how the lock casing is provided with a reduced portion 40 at the top thereof and with a second reduced portion 41 at the bottom thereof, the reduced portion 40 being longer than the reduced portion 41. In inserting the lock casing through the opening, the casing is tilted with respect to the cabinet and then the reduced portion 40 is moved through the opening 39, and then upwardly until the shoulder 42 of the casing 45 abuts the upper edge of the opening 39. The lock casing may now be swung into a vertical position, and this will swing the portion 41 past the lower edge 43 of the opening. The lock casing is now lowered 50 until the shoulder 44 of the casing abuts the edge 43. The lock is now disposed in the position shown in Figure 6, and it will be noted from this Figure that the portion 40 still engages with the wall *x*, and this, together with the portion 41, prevents the removal of the lock casing from the cabinet.

55 In Figure 7, I show a strap 45 for locking all of the casings in the cabinet. The strap carries studs 46, and these studs bear against the tops of the lock casing, see Figure 6, and

when the strap 45 is prevented from movement, the studs will prevent the removal of the lock casings from the cabinet. The upper end of the strap 45 is passed through a lock 47. This lock may be opened or 70 closed by means of a key, and when locked will prevent the movement of the strap 45, thus locking the lock casings in place. If a key of one of the lock casings should be lost, the strap 45 could be released to permit the 75 removal of the lock casing and the substitution of a new one.

Deflector plates 48 are disposed beneath each lock casing and guide the coins away from the lock casings disposed directly beneath. The coins will drop into a coin box 80 49 where they may be removed at any time.

I claim:

1. A device of the type described comprising a body portion having a coin passageway therein, a key-actuated cylinder, means for stopping the movement of said cylinder when no coin is inserted in the device, and means operatively connecting said cylinder with said stop means for causing 85 said stop to engage said cylinder when said cylinder is turned without inserting a coin, said connecting means being arranged to close the coin entrance when the key has 90 been removed.

2. A device of the type described comprising a body portion having a coin passageway therein, a key-actuated cylinder, means for stopping the movement of said cylinder when no coin is inserted in the device, means operatively connecting said cylinder with said 100 stop means for causing said stop to engage said cylinder when said cylinder is turned without inserting a coin, said connecting means being arranged to close the coin entrance when the key has been removed, an indicator carried by said body portion, and means operatively connecting said indicator with said connecting means.

3. A device of the type described comprising a body portion having a coin passageway therein, a key-controlled cylinder having a recess therein, a closure for said coin passageway adapted to be actuated by the movement of said cylinder, said closure 110 having a projection normally bearing against the cylinder and being receivable in said recess, said projection engaging with the key in said cylinder for preventing movement of said closure into operative position, and 115 yielding means for moving said closure into operative position when said key is removed from said cylinder.

4. A device of the type described comprising a body portion having a coin passageway therein, a key-controlled cylinder, a stop member for normally preventing the actuation of said cylinder when no coin has been inserted, and means operatively connecting said cylinder with said stop member 120 125 130

for actuating said stop member, said means being constructed to support the coin in a position adjacent to said stop member, whereby the coin will prevent the movement of the stop member, thus permitting the cylinder to be actuated.

5. A device of the type described comprising a body portion having a coin passage-way therein, a key-controlled cylinder, a stop member for said cylinder for preventing the turning of said cylinder when no

coin has been inserted, a lever for moving said stop member, an arm connected to said cylinder for actuating the locking bolt, said arm bearing against said stop member, and a spring means bearing against said lever and being operatively connected to said arm to exert a greater force upon said arm than upon said stop member, whereby said stop member is prevented from movement into operative position by said arm.

WILLIAM J. DOBKIN.
